UNITED STATES PATENT OFFICE.

FRANK E. HARTMAN, OF SCOTTDALE, PENNSYLVANIA, ASSIGNOR TO ELECTRIC WATER STERILIZER AND OZONE COMPANY, OF SCOTTDALE, PENNSYLVANIA, A CORPORATION OF PENNSYLVANIA.

SWIMMING POOL.

Application filed April 22, 1922. Serial No. 556,050.

To all whom it may concern:

Be it known that I, FRANK E. HARTMAN, citizen of the United States, residing at Scottdale, in the county of Westmoreland and State of Pennsylvania, have invented 5 certain new and useful Improvements in Swimming Pools, of which the following is a specification.

This invention relates to an improved 10 circulating apparatus for swimming pools or tanks of the type usually constituting a part of the equipment of athletic institutions, gymnasiums, community centers or other more or less public bathing places.

15 A primary object of the invention is to provide a simple and practical circulating apparatus for swimming pools and the like whereby reused purified water may be supplied at the bottom of the pool while the used water may be removed from the top, thereby obtaining effective distribution of the fresh water to keep the temperature of the tank uniform throughout and also removing the impurities floating upon the 20 surface of the water or held in suspension by the upper and lighter strata of the water.

25 A further object of the invention is to provide means for automatically replenishing the water used in the circulating system thereby to maintain the same of maximum efficiency at all times without manual attention if the apparatus has been once set in motion. In that connection the invention 30 aims to provide a device that acts more or less as a pilot for controlling the supply of fresh water when conditions require.

35 A further object of the invention is to provide simple, practical and reliable means 40 for straining or separating the water in its progress through the circuit thereby removing solid or other floating matter. That is to say the invention proposes to provide a novel device that arrests or collects and 45 automatically disposes of solid matter in a practical and efficient manner.

With the above and other objects in view 50 which will more readily appear as the nature of the invention is better understood, the same consists in the novel construction, combination and arrangement of parts herein- 55 after more fully described, illustrated and claimed.

A preferred and practical embodiment of the invention is shown in the accompanying 55 drawings:

Figure 1 is a plan view of my improved swimming pool and the combined circulating and purifying system therefor.

Figure 2 is a longitudinal sectional view 60 thereof, certain of the elements of the system being diagrammatically shown.

Figure 3 is a vertical sectional view.

Figure 4 is an enlarged top plan view of 65 the sump.

Similar reference characters designate corresponding parts throughout the several figures of the drawings.

As previously indicated the present invention aims to provide a swimming pool 70 having a novel circulating and purifying system which reuses the water in the pool in a most economical manner and yet at the same time maintains a high standard of purity therefor.

75 Heretofore, it has been the general practice to supply the fresh water at the top and to withdraw the used water from the pool at the bottom. This practice tends to only dilute instead of thoroughly cleanse the 80 surface water and is obviously objectionable. As bathers are in contact with the surface water more frequently than at deeper levels, and the upper strata of water become more quickly contaminated than the lower strata 85 it is important that the surface water be maintained at the highest possible degree of purity.

Also since the water in the tank requires 90 heating during the greater portion of each year, when this warm water is introduced at the top it tends to remain on the surface and forms strata of warm and cold water. This practice therefore approaches a condition of stagnation because no definite 95 stream lines can be established from the surface of the water to the point of exit at the bottom. Under conditions such as this bacteria introduced into the pool of water by the bathers will remain in suspension 100 and multiply. To depend entirely upon the rise of water in the tank due to a sufficient number of bathers entering the pool to discharge this bacteria or foreign matter into the so-called overflow is not practical 105 or feasible. Therefore, it will be under-

stood that where no definite and positive means of circulating the water in the tank is provided, dangerous conditions are likely to result.

- 5 In installations where purification is attempted by displacing used water with fresh water, the water which goes to waste over the overflow trough makes a considerable total loss when it is observed that in some 10 cases the average loss at this point amounts to 10 inches of water per day, totaling anywhere from one to two million gallons of water per year. Obviously, therefore, from an economical standpoint systems which provide for replacing with fresh water the used water which goes to waste is very costly.

The present apparatus is intended to overcome the objections above set forth and to that end it is proposed to equip the pool A 20 with a novel circulating system which includes a sump device B for receiving the overflow water from the pool A and also controlling the supply of fresh water from the line C to the system. That is to say, the 25 sump device B is provided with a float valve device to be hereinafter more fully referred to which automatically operates when the level of water in the sump falls below a predetermined point to admit fresh water into 30 the system to fully maintain the liquid capacity of the system and prevent the pump device D from sucking air.

After the pump device D removes the water from the sump B it may be passed 35 through the filter device E, heater F and ozonizer G, which latter includes a generator H for providing ozone and a mixer I for thoroughly treating the water with ozone.

In its general aspect therefore the present 40 invention includes the pool A which is equipped with a circulating system maintained at full capacity by the sump device B and which includes suitable piping for feeding the purified water at the bottom 45 of the tank while the used water is removed from the top.

Referring now more particularly to the details of construction it will be observed that the pool or tank A is formed with a 50 bottom 5 and surrounding walls 6, formed with an overflow trough 7 for the surface water of the tank. This trough surrounds the tank and is inclined to direct the overflow water to a common discharge outlet 8, and 55 from this outlet, the overflow water is carried through a pipe 9 into the sump B. Extending below the bottom of the tank and preferably arranged centrally of the tank is a warm water feed pipe 10 which communicates with the bottom of the tank at a plurality of points by means of inlet pipes 11, thereby distributing the warm water effectively upwardly and outwardly throughout the pool.

60 A drain outlet 12 may be provided in the

bottom of the tank and connected to the sewer to permit of the entire contents to be removed when necessary.

The sump B, which receives the overflow water, consists of a chamber provided with a partition or wall 13 having a strainer 14 for removing the foreign matter brought with the overflow water from the tank. The said strainer 14 is placed in the inclined front section 13^a of the wall beneath the lower end of the pipe 9, said pipe having a horizontal discharge opening 9^a which directs the water against the inclined strainer so that floating matter, i. e., solid matter held in suspension will be caught by the strainer immediately upon issuing from the delivery pipe 9 and will be washed over the edge of the wall 13^a by the force of the water, and onto the rearwardly inclining section 15 of the wall 13, which slopes in the opposite direction from the section carrying the strainer. This section 15 is imperforate and joins the vertical portion 16 having openings 16^a of the partition to form the trap T having the outlet passage 17. Thus 90 foreign matter which has been washed from the crest 18 formed between the inclined sections 13^a and 15 will be carried downwardly on the imperforate portion of the partition, and thence into the trap T from 95 which it can be removed through passages 17 by the water that splashes over the crest 18 and also flows out through the opening 16^a.

The raw water supply or pipe C communicates with the interior of the sump B 100 at a point under the wall 13, as indicated by the numeral 19. This main water inlet pipe is controlled by a float valve 20 located within the sump, as will presently appear.

The pump D operates to pump the water 105 from the sump through a pipe 21 to the filter E, from whence the water is circulated through a pipe 22 to the heater F, and from the heater F the warm water is circulated through a pipe 23 to the upper end of the ozonizer G. The filter E, heater F and ozonizer G are all more or less diagrammatically shown.

The heated water is then mixed with ozone in the mixer I and the mixture is then 115 circulated through a discharge pipe 24 into the warm water feed pipe 10 previously described.

From the foregoing it will be observed 120 that when the tank is to be filled with water, the pump D will be operated to exhaust the contents of the sump thereby causing the float valve 20 to be lowered and thereby let in the raw water. When the pool A is filled, water will overflow into trough 7 and then 125 proceed to the sump. When the water reaches a predetermined level in the sump, the float valve 20 shuts off the raw water. If the water level in the tank tends to drop either from evaporation or by the water be- 130

ing carried away by the bathers, the valve 20 will be automatically opened and a sufficient amount of raw water will be received to automatically and constantly maintain

5 the water in the tank at its peak so that there is a constant overflowing of the surface water back into the sump. Inasmuch as the trough 7 surrounds the tank, the surface water is constantly moving outwardly 10 in all directions. By reason of the fact that the warm water is introduced at a plurality of points at the bottom of the tank, said water will naturally rise to the surface and thereby set up stream lines running from 15 the bottom to the top of the water. Furthermore because the inlet pipes 11 are arranged in spaced relation, a plurality of these stream lines in different positions of the tank will be created and all floating matter 20 held in suspension in any part of the water in the tank will be carried upwardly to the surface and consequently this surface water, together with the suspended foreign matter, will be carried off through the 25 trough 7 to the sump.

The trap in the sump then serves to separate the foreign matter carried by the overflow water from said water and discharge said foreign matter through the outlet 17, the separated water entering the sump, and being subsequently pumped through the filter E where any further impurities or foreign matter will be removed, thence through the heater F and thence through the ozonizer G and back to the bottom of the tank. 35 It will, therefore, be seen that the overflow water is used over and over again, and that the ozonizer purifies the water prior to its entrance into the tank.

40 It will furthermore be noted that the automatic float valve 20 of the sump serves to prevent the water level of the sump from falling below a predetermined point, and by this means the loss of water from the tank, due to the evaporation or otherwise, is automatically replenished and the water in the tank is maintained at a constant level.

Without further description it is thought that the features and advantages of the invention will be readily apparent and it will 45 of course be understood that changes in the form, proportion and minor details of con-

struction may be resorted to without departing from the spirit of the invention or scope of the appended claims.

55

I claim:

1. A circulating system for swimming pools including an overflow gutter for removing the surface water and floating foreign matter, a sump device for receiving 60 said overflow water, a strainer in said device for separating the foreign matter from the overflow water, a valved raw water inlet pipe communicating with the sump device piping for supplying water to the bottom 65 of the pool, and heating and purifying means included in the circuit between the sump and the said piping.

2. In a circulating system for swimming pools, an overflow gutter, a sump device including an inclined strainer, and a conduit leading from said gutter and discharging onto said inclined strainer of the sump device.

3. In a circulating system for swimming 75 pools, an overflow gutter for removing surface water, a sump device including a strainer and a trap at one side thereof and means for conveying water from the overflow gutter onto the strainer whereby foreign matter will be separated and washed 80 over into the trap.

4. In a circulating system for furnishing purified water to swimming pools, an overflow gutter surrounding the pool, a sump device including a strainer and a solid matter trap, means for directing surface water from the overflow gutter onto the strainer, a pump connected with said sump, and heating and purifying instrumentalities for receiving 90 water from said pump, and piping means for feeding said purified water to the bottom 85 of the tank.

5. A circulating system for swimming pools, including an overflow gutter for removing the surface water and floating foreign matter, a sump device in piped communication with said overflow gutter including a strainer and a solid matter trap, and means for returning the overflow water to 95 the pool.

In testimony whereof I hereunto affix my signature.

FRANK E. HARTMAN.
